UNITED STATES PATENT OFFICE.

MAURICE L. WILLARD, OF CHICAGO, ILLINOIS, ASSIGNOR TO SUPERIOR TYPE COMPANY, A CORPORATION OF ILLINOIS.

TYPE-HOLDER FOR STAMPS.

1,190,497.

Specification of Letters Patent. Patented July 11, 1916.

Application filed January 2, 1915. Serial No. 134.

To all whom it may concern:

Be it known that I, MAURICE L. WILLARD, a citizen of the United States, residing at Chicago, in the county of Cook and State of Illinois, have invented certain new and useful Improvements in Type-Holders for Stamps, of which the following is a specification.

My invention relates in general to type 10 rubber holders, and more particularly to holders for removably retaining individual rubber type in desired relative arrangement in a hand-printing stamp.

It is desirable in the use of printing 15 stamps that the type should be evenly supported in alinement, so that the letters or numerals of the matter printed by the stamp may be uniform. It is further desirable that a holder should be provided in which the 20 type may be conveniently set up, and which will firmly retain the type without interfering with the ready removal thereof when it is desired to set up other matter in the holder.

The primary object of my invention is to 25 provide a type holder for stamps in which the type may be readily set up in uniform alinement, and which will firmly retain the type in their set-up relation, and from 30 which the type may be easily removed.

A further object of my invention is to 35 provide a type holder which will be simple in construction, efficient in use, and inexpensive in manufacture.

My invention will be more fully disclosed 40 hereinafter with reference to the accompanying drawings, in which the same is illustrated and described as embodied in several convenient and practical forms, and, 45 in which,

Figure 1 is a side elevation and view of a hand stamp, a part being broken away for the purpose of clearer illustration. Fig. 2 is a cross-sectional view on the line 2—2 of 45 Fig. 1. Fig. 3 is a cross-sectional view showing a modified form of my invention. Fig. 4 is a similar view of another form of my invention. Fig. 5 is a similar view of still another embodiment of my invention. 50 Fig. 6 is a similar view showing my inven-

tion embodied in a form having a plurality of type-holding grooves. Fig. 7 is a perspective view from the under-side of one end of the form of my invention shown in Fig. 5, and Fig. 8 is a perspective view of 55 a type.

Similar reference characters are used to designate similar parts in the several figures of the drawings.

Reference character A indicates a holder, 60 preferably formed of metal bent into channel shape, the ends and bottom of the channel being open.

B indicates a handle secured to the holder A for affording convenience in using the 65 stamp.

C designates a chase preferably formed of resilient material, such as rubber, having therein a channel closed at its ends and open at its bottom. The width of the channel 70 corresponds to the width of the type to be received therein, and the depth of the channel is so related to the height of the type that the type will project below the channel. The lower edges of the chase are 75 substantially flush with the lower edges of the side flanges of the holder, in order that the type may be securely supported within the chase throughout the depth of the channel therein. In other words, the side flanges 80 of the holder serve to retain the walls of the channel in the chase in engagement with the type, so as to securely support the type when in use.

In the form of my invention shown in 85 Figs. 1 and 2, the chase C is provided with a channel of uniform rectangular cross-section between the walls of which the type D closely fit so as to be held in proper set-up relation against accidentally falling out of 90 the chase. In order that the type may extend the entire depth of the channel and be uniformly gripped by the side walls thereof, I have found in practice that it is desirable to slightly widen the channel at the 95 top thereof, which may be conveniently done by slightly diverging the side walls thereof, as indicated at c¹ in Fig. 3. In order to more securely retain the type within the chase, I have also found it advantageous to 100

provide the inner supporting walls of the channel with inwardly projecting ribs. I have shown such a modified form of my invention in Fig. 4, in which C^2 designates the chase, c^2 the divergence along the upper edge of the side walls of the channel, and e^2 the inwardly projecting ribs along the inner surfaces of the supporting walls of the channel. The inwardly projecting ribs within the channel may be used with advantage when the supporting walls of the channel do not diverge along the upper edges, and I have shown such a modified form of my invention in Fig. 5. In this figure, C^3 designates the chase and e^3 a plurality of parallel ribs projecting into the channel from the supporting walls thereof.

My improved rubber type holder is adapted to support a plurality of rows of rubber type by merely providing a plurality of channels in the resilient chase. In Fig. 6 the chase C^4 is provided with three parallel type-receiving channels, the supporting walls of each channel being shown as diverging along their upper edges, as indicated at c^4 .

e^4 indicates pairs of parallel ribs projecting into the channels from the supporting walls thereof.

In the use of my invention the type D are set up in the chase in any desired arrangement. When the number of type is insufficient to completely fill the channel lengthwise, the space in the channel not occupied by the type may be filled by quads, such as indicated at F in Fig. 1. The resiliency of the chase serves to securely retain the type therein, without however interfering with the ready removal of the type when it is desired to set up other matter in the stamp. The resiliency of the material of which the chase is formed serves to cushion the type so that they will be yieldingly supported and thereby produce uniform impressions, that is the chase forms a cushion support for the type in order that should they be unevenly arranged in the chase such unevenness will be compensated for by the yielding of the chase. The divergence along the upper edges of the walls forming the type-receiving channel permits the type to extend the entire depth of the channel, so that all of the type will have a uniform projection below the chase. The provision of the inwardly projecting ribs on the supporting walls of the channel renders more secure the retention of the type in the channel.

From the foregoing description it will be observed that I have invented an improved holder for the type of stamps for printing and marking purposes, by means of which the type are removably held in uniform alinement, and which permits the type to be readily set up and easily removed.

I claim:

1. In a stamp for printing and marking

purposes, the combination with a chase having a channel therein the opposing walls of which are made of rubber to receive type between them, the width of said channel being slightly greater adjacent its top, of a plurality of type removably fitting between the rubber walls of said channel with their upper ends lying within the widened portion of said channel.

2. In a stamp for printing and marking purposes, the combination with a chase having a channel therein open at its bottom and formed between parallel rubber walls, the walls of said channel diverging at their upper edges, of a plurality of rubber type of a shape to closely fit between the parallel walls of the channel and to project below the chase in alinement with the channel, and a holder within which said chase is supported.

3. In a stamp for printing and marking purposes, the combination with a chase formed of rubber and having a channel therein to receive type, of ribs projecting into said channel from the side walls thereof, and a plurality of type of a shape to closely fit between the supporting walls of said channel and to be retained therein by said ribs.

4. In a stamp for printing and marking purposes, the combination with a chase formed of non-metallic resilient material having a channel therein open at its bottom and formed between parallel walls, the walls of said channel diverging at their upper edges, of ribs projecting into said channel from the side walls thereof, and a plurality of type of a shape to closely fit between the supporting walls of said channel and to be retained therein by said ribs.

5. In a stamp for printing and marking purposes, the combination with a chase formed of rubber material, having a channel therein open at its bottom and formed between parallel walls, the walls of said channel diverging at their upper edges, of ribs projecting into said channel from the side walls thereof, a plurality of type of a shape to closely fit between the supporting walls of said channel and to be retained therein by said ribs, and a holder within which said chase is supported.

6. In a stamp for printing and marking purposes, a chase formed of resilient material having a type-receiving channel therein open at its bottom and formed between supporting rubber walls which diverge at their upper edges.

7. In a stamp for printing and marking purposes, a chase formed of non-metallic resilient material having a type-receiving channel therein open at its bottom and formed between walls which diverge at their upper edges, and ribs projecting inwardly from the side walls of said channel

to yieldingly retain the type within the channel.

8. In a stamp for printing and marking purposes, the combination with a rubber chase having a channel therein to receive rubber type, of ribs projecting into said channel from the side walls thereof, and a plurality of rubber type of a shape to closely fit between the supporting walls of said

channel and to be retained therein by said ribs.

In testimony whereof, I have subscribed my name.

MAURICE L. WILLARD.
